[57] CLAIM

The ornamental design for a combined key holder and defensive weapon, substantially as shown and described.

DESCRIPTION

FIG. 1 is a front elevational view of a combined key holder and defensive weapon showing my new design;
FIG. 2 is a right side elevational view thereof;
FIG. 3 is a rear elevational view thereof;
FIG. 4 is a left side elevational view thereof;
FIG. 5 is a top plan view thereof;
FIG. 6 is a bottom plan view thereof; and
FIG. 7 is an elevational view thereof in the open condition, the environmental structure shown in FIGS. 1 and 7 being for illustrative purposes only.
